UNITED STATES PATENT OFFICE.

WILSON HATCH TUCKER, OF MONTCLAIR, NEW JERSEY, ASSIGNOR TO LORD & TAYLOR,
A CORPORATION OF NEW YORK.

COLD-STORAGE INSTALLATION.

1,268,301.

Specification of Letters Patent. Patented June 4, 1918.

Application filed August 17, 1914. Serial No. 857,191.

To all whom it may concern:

Be it known that I, WILSON HATCH TUCKER, a citizen of the United States, residing in Montclair, Essex Co., New Jersey, 5 have invented certain new and useful Improvements in Cold-Storage Installations, of which the following is a full, clear, and exact description.

My invention relates to cold storage installations and particularly to the type in 10 which furs and other articles which it is desirable to protect from moths, are stored.

One object of my invention is to provide 15 such a cold storage installation in which cold air is made to circulate continuously without the aid of a fan or other mechanical means.

Another object is the provision of means whereby fresh, pure air may be substituted 20 for the vitiated air within the storage compartments, when necessary.

Still another object is the provision of means whereby the loss due to the escape of 25 cold air when an attendant enters the storage compartments is reduced to a minimum.

Other objects and advantages will appear from the description and claims which follow.

The single sheet of drawing illustrates a 30 longitudinal section of my cold storage installation. In the drawing 1 represents the cooling or refrigerating chamber in which is located the refrigerating coil 2, through which a suitable refrigerating fluid such as 35 ammonia circulates. The refrigerating chamber is provided with two inlet openings 3, 4, located in the upper portions of the opposite side walls and with the two outlet openings 5, 6, located in the lower wall.

40 Each of these openings is provided with a suitable door for closing the same. Adjacent the cooling chamber and extending partially thereunder on either side are the storage compartments 7, 8. These compartments 45 are separated by the wall 9 in which is located a door 10, which may be opened to allow the two compartments to communicate with each other, as will be hereinafter described. In the outer walls of the storage

50 compartments 7, 8, are the doors 11, 12, respectively, which may be utilized to permit a person to enter therein. As clearly shown in the drawing, my installation extends throughout two stories. The doors 11, 12 55 are located near the top of the second story

for a purpose which will appear hereinafter. Within the storage compartments are located suitable clothes racks 13 supported on cross beams 14, which beams also serve as walking beams for the attendants. The ladders 15 60 are provided to convey the attendants to the high racks. The doors 16, 17, 18, 19 are provided in the ceiling, whereby pure air may be substituted for the vitiated atmosphere within the installation, when desired. 65

The doors 16, 17 are also useful as an exit for the steam, when hot water is run through the cooling pipes to remove the frost from the exterior thereof.

The normal operation of this installation 70 is as follows: The air within the cooling chamber as it is reduced in temperature, sinks to the bottom of the chamber and escapes through the outlet openings 5, 6, thereby entering the storage compartments 75 7, 8, respectively. After passing into the storage compartments, the air is slightly heated and therefore rises to the top of the storage compartments and again enters the cooling chamber through the inlet openings 80 3, 4. In this way a constant circulation of cool air is maintained from the cooling chamber through the openings 5, 6, through the storage compartments 7, 8, and thence into the cooling chamber through the openings 3, 4. By locating the doors 11, 12 in the position shown, the amount of loss by reason of the escape of cold air, when the doors are opened to permit the entrance of the attendant, is reduced to a minimum. If 90 the doors were placed at the level of the first floor, a very much larger amount of cold air would escape because at that point the general direction of the circulation is horizontal, and also because the difference in 95 temperature between the outside atmosphere and the air of the storage compartments is greater at the bottom than it is nearer the top. At the point where I have located the doors, on the other hand, the general direction 100 of the circulation is vertical and the difference in temperature is less, so there is very little tendency for the cold air to escape when the doors 11, 12 are opened. If it is found to be inconvenient to locate the doors 105 at the places indicated by 11, 12, they may be located at the places 11', 12'. When so located the advantages above pointed out are still present, but to a slightly less degree.

If it is desired to use but one storage com- 110

partment, for instance, the compartment 7, this may be accomplished by closing the openings 4, 5. This same result may also be obtained by closing the inlet opening 4 5 while the opening 5 remains open and by opening the door 10 in partition 9. With this latter arrangement the cooling air from both openings 5, 6, enters the compartment 7.

- 10 When it is desired to renew the air within the installation, by substituting pure atmospheric air therefor, the doors 3, 4, are closed, and the doors 16, 17, 18, 19 opened, so that fresh air enters the cooling chamber 15 through doors 16, 17 and passes thence through the openings 5, 6, forcing the vitiated air out through the doors 18, 19. After this operation has been carried on for a short time, the vitiated air of the storage 20 compartments will have been completely replaced by fresh pure air. When this has been accomplished the doors 16, 17, 18, 19 are closed, and the doors 3, 4, opened to allow the air to circulate entirely within 25 the installation.

The advantages of my installation are obvious, from the above. I do not desire to limit myself to the particular embodiment shown herein, but obviously many 30 changes may be made therein without departing from the spirit of my invention.

What I claim is:

1. In a cold storage installation, the combination of a plurality of adjacent communicating storage compartments having a common side wall provided with means for putting the said compartments into communication, a single refrigerating chamber located partially within each of said compartments adjacent the tops thereof and provided adjacent its bottom with a plurality 35 40

of outlet openings, one of which communicates with one of said compartments, and, adjacent its top, with a pair of inlet openings one of which communicates with one 45 of said compartments, and a closure for each of said openings, whereby each compartment may be independently supplied with cold air through its corresponding outlet opening, or a single compartment 50 may be supplied with cold air through both of said outlet openings, as desired.

2. In a cold storage installation, the combination of a plurality of adjacent communicating storage compartments having a common side wall provided with means for putting said compartments into communication with each other, each compartment being provided adjacent its top with a doored opening for the entrance of an attendant therein, a single cooling chamber located partially within each of said compartments adjacent the tops thereof, and provided, adjacent its bottom, with a plurality of outlet openings, one of which communicates with one of said compartments, and, adjacent its top, with a plurality of inlet openings, each of which communicates with one of said compartments, and a closure for each of said openings, whereby each 65 compartment may be independently supplied with cold air through its corresponding outlet opening, or a single compartment may be supplied with cold air through both of said outlet openings, as desired, said 70 chamber being provided with a door opening to the chamber whereby pure air may be admitted thereto.

WILSON HATCH TUCKER.
